(57) **CLAIM**

The ornamental design for a display device, as shown and described.

DESCRIPTION

FIG. 1 is a perspective view of a display device showing my new design.

FIG. 2 is a front elevational view of the display device of FIG. 1.

FIG. 3 is a rear elevational view of the display device of FIG. 1.

FIG. 4 is a top plan view of the display device of FIG. 1.

FIG. 5 is a bottom plan view of the display device of FIG. 1.

FIG. 6 is a right side elevational plan view of the display device of FIG. 1; and,

FIG. 7 is a left side elevational view of the display device of FIG. 1.

The broken lines in FIG. 2 illustrate portions of the display device and form no part of the claimed design.

1 Claim, 5 Drawing Sheets
